UNITED STATES PATENT OFFICE

165,473

PLAY SUIT

Tina Leser, New York, N. Y.

Application March 21, 1951, Serial No. 14,568

Term of patent 3½ years

(Cl. D3—17)

To all whom it may concern:

Be it known that I, Tina Leser, a citizen of the United States, residing in New York city, in the county of New York and State of New York, have invented a new, original, and ornamental Design for a Play Suit, of which the following is a specification, reference being had to the accompanying drawing, forming part thereof.

Fig. 1 is a front view of a play suit, showing my new design;

Fig. 2 is the rear view thereof;

Fig. 3 is another front view of the play suit shown in Fig. 1 on a slightly increased scale, illustrating the bloomer portion in untied position; and

Fig. 4 is the rear view thereof on a reduced scale.

I claim:

The ornamental design for a play suit, substantially as shown.

TINA LESER.
